CLAIM

The ornamental design for a tissue box, as shown and described.

DESCRIPTION

FIG. 1 is a front perspective view of a tissue box with a lid attached;

FIG. 2 is the front perspective view of the tissue box, showing a lid partially detached with an exemplary hand;

FIG. 3 is the front perspective view of the tissue box, showing the lid as detached from the tissue box;

FIG. 4 is the front perspective view of the tissue box following detachment of the lid;

FIG. 5 is the front perspective view of the tissue box, shown in a position of use with exemplary tissues;

FIG. 6 is a top plan view of the tissue box;

FIG. 7 is a bottom plan view of the tissue box;

FIG. 8 is a right side view of the tissue box;

FIG. 9 is a left side view of the tissue box;

FIG. 10 is a front side view of the tissue box; and,

FIG. 11 is a back side view of the tissue box.

The dashed lines in the drawings depict the environment and form no part of the claimed design.
